FILM CARTRIDGE

Robert J. Roman, Rochester, N.Y., assignor to Eastman
Kodak Company, Rochester, N.Y., a corporation of
New Jersey

Filed Nov. 1, 1966, Ser. No. 4,507

Term of patent 14 years

(Cl. D61—1)

FIG. 1

FIG. 2

FIG. 3

FIG. 4

FIG. 5

FIG. 6

FIG. 7

FIG. 8

FIG. 9

FIG. 10

FIG. 1 is a perspective view showing the front and top left of a film cartridge, showing my new design;

FIG. 2 is a perspective view showing the front and top right thereof;

FIG. 3 is a perspective view showing the rear and bottom thereof;

FIG. 4 is a top view thereof;

FIG. 5 is a front elevational view thereof;

FIG. 6 is a bottom view thereof;

FIGS. 7 and 8 are elevational views of the left and right sides, respectively, thereof;

FIG. 9 is a rear elevational view thereof; and

FIG. 10 is a sectional detail, taken substantially on line 10—10 of FIG. 9.

I claim:

The ornamental design for a film cartridge, as shown.
